UNITED STATES PATENT OFFICE.

JAMES G. HARDIE, OF CANTON, NEW YORK.

SHEET-FEEDING MACHINE.

Application filed March 21, 1922. Serial No. 545,551.

To all whom it may concern:

Be it known that I, JAMES G. HARDIE, a citizen of the United States of America, and a resident of Canton, county of St. 5 Lawrence, and State of New York, have invented certain new and useful Improvements in Sheet-Feeding Machines, of which the following is a specification.

The present invention relates to improvements in a sheet-feeding mechanism for printing presses and the like, in which a single sheet is fed off a stack and carried forward to the impression cylinder, and relates in particular to means to carry the 15 sheet at first rapidly and then move it slowly forward to the cylinder guides, to avoid rolling the front edge of the sheet as it contacts the cylinder guides.

My present invention relates to improved 20 features of construction particularly as follows: a rear set of receiving tapes or the like to move the sheet rapidly forward as it is delivered upon said tapes by a feed-roll or other mechanism, then to advance the 25 sheet by its being taken hold of by a reciprocating set of grippers or the like, and to deposit the sheet upon a slowly running set of tapes that will place the sheet against the cylinder grippers.

30 In order that my invention may be fully understood, I shall first describe it with reference to the accompanying drawings, and afterward more particularly point out the novelty of each feature.

35 In the accompanying drawings similar figures refer to similar parts.

Fig. 1 is a side elevation of what is known as the feeder's side, showing the rear of a printing press including the impression cylinder. A side view of the elevator is shown 40 in outline, with a stack of paper upon an elevator platform. Also are shown the rear, fast-running tapes, the reciprocating carriage, and the front, slow-running tapes; also is shown the means for transmitting 45 power from the press-driving shaft to the feeder.

Fig. 2 is a plan view showing the parts heretofore referred to.

50 Inasmuch as my present invention relates in particular to means for advancing the sheet from the stack of sheets to the press cylinder, I have not shown the mechanism for elevating the stack, nor for lifting the 55 sheets singly. Reference is made here to

my application, Serial No. 272,225, filed on January 21, 1919, and allowed on December 21, 1921, in which are shown the mechanism for lifting the elevator platform and the suction means for lifting the sheets 60 singly and carrying them forward to the main feed-roll and around said feed-roll the present fast-running rear tapes pass; therefore it is practically at the feed-roll where this present invention begins. 65

I have not shown also the side-registering mechanism, as the mechanism illustrated in my Patent No. 1,144,937, issued on June 29, 1915, is applicable.

Description in detail.

Fig. 1, 1 is the press-frame, 2 is the stack of sheets, which may be elevated in various ways; however, I have shown chains passing over sheaves upon parallel shafts; 3 75 are the side-bars and 4 the supporting legs. The power is received from the driving shaft 5 of the printing press, and through the chain and sprockets 6, the beveled gears 7, the shaft 8, the worm 24, and the worm-gears 9, the shaft 10 is rotated. The parts are so designed that the shaft 10 will make one revolution to each complete reciprocation of the type-bed, or to each sheet 80 printed. On the shaft 10 is mounted the arm 11, and pivotally attached to it is the link 12, the link is also pivotally attached to the arm 13, which arm is mounted on the shaft, 14, 15 is a link pivotally attached to the arm 13 and the reciprocating carriage 16, 17 are ways pivotally attached to the frame 18, 19 is a power-driven main feed-roll carrying the tapes 20, 21 is a drop-roll adapted to contact the tapes 20, to hold the in-coming sheet upon the tapes; 22 is 85 a set of tapes mounted in the frame 18, and upon these slow-running tapes the sheet is dropped from the reciprocating carriage 16, 23 is a chain which rotates the tapes 22. 90 25 is a printing press cylinder guide against 95 which the slow running tapes place the sheet. 100

Manner of operation.

The power is taken from the press-shaft 105 5, and transmitted through the chain and its sprocket 6, through the beveled gears 7 and the shaft 8 to the worm 24, which engages the worm-gear 9 upon the shaft 10. Thus, at each to-and-fro movement of the type- 110

bed the shaft 10 will make one complete revolution, and through the arm 11 and the link 12 which is pivotally attached to the arm 13, the arm 13 will be rocked to and fro at each revolution of the shaft 10, this means will have the effect to move the reciprocating carriage 16 back and forth. On each side of the machine are arm 13 and the link 15. The sheets are fed singly to the feed-roll 19 by mechanism illustrated in my application, Serial No. 272,225, allowed on December 21, 1921. The drop-roll 21 will contact the feed-roll tapes so as to make the movement of the sheet positive, and thus the sheets will be carried upon the tapes 20, and so timed as to meet the reciprocating carriage on its backward stroke; grippers or other mechanism will be carried upon the carriage to take hold of the sheet and any form of gripper mechanism now in use may be used; and as the gripper mechanism does not form a part of this invention I have not illustrated such means. The reciprocating carriage 16, when it has taken hold of the front edge of the sheet, will then make its forward travel, and at a predetermined point the gripper mechanism will let go of the sheet, and it will drop onto the slow-moving tapes 22, and by them the sheet will be carried against the cylinder guides.

It will be observed that the spirit of the invention herein outlined is that the sheet will first be carried upon tapes running at a high rate of travel, and then positively taken hold of by grippers or the like, and then positively carried forward over a set of tapes running at a much slower rate of speed than the first set of tapes run, so that as the sheet is carried forward against the cylinder guides it will not have its front edge rolled nor creased by the impact with the cylinder guides.

Reference is made to my Patent No. 1,144,937, in which is illustrated a framework and a side-register that are applicable; so I have not shown the details of the frame 18 and the mechanism for rotating the tapes 22, nor the side-registering mechanism.

I have illustrated this forwarding mechanism with a stack of sheets on an elevator platform, and which is known to the trade as a pile elevator feeder, but I do not confine myself to this form of feeder, for this design of a reciprocating sheet-carrier and a frame-work on the press-table, containing a slow-running set of tapes, is applicable to other designs of feeding machines, such as are known to the trade as continuous feeders; I wish, therefore, to use this forwarding mechanism in connection with any design of feeder as a means to deliver the sheet to the press cylinder guides.

Various designs of folding ways can be used, upon which the reciprocating carriage

travels, hence I do not confine myself to any particular form.

I have not shown any particular design of reciprocating carriage 16, for various forms will be practicable, nor do I confine myself to the use of gripper mechanism to take hold of the sheet for it may be desirable to take hold of the sheet by suction and any form of sucker can be used only that it engages the sheet at a predetermined time and then to shut off the air at a predetermined point. Therefore I wish to use either mechanical parts or any form of suction to take hold of the sheet.

I have shown a reciprocating gripper device for advancing the sheet from the fast running tapes to the slow running tapes, but I do not confine myself to a reciprocating device as various designs of a rotary gripper which is in use could be used to accomplish the same ends. So I desire to use any practicable means to forward the sheet.

I have illustrated my invention as used in connection with a printing press, but it can be adapted to any mechanism to which sheets are fed singly, so I do not confine its use to printing presses only.

I have illustrated my invention in the form of a sheet-feeding machine, feeding single sheets from a stack of paper to the cylinder of a printing press; but I do not confine myself to that form only, as sheets may be fed from a cylinder of a printing press to a second cylinder, so I wish to cover the use of my invention also in carrying a sheet from one impression cylinder to another cylinder be it in the same press or in the case of distinct and separate presses.

Having thus described my invention, what I claim is:

1. In a sheet feeding-machine, means adapted to advance a sheet to a predetermined position, means adapted to forward said sheet and deposit it upon a slower moving means, adapted to position said sheet against cylinder guides or other stops.

2. In a sheet-feeding machine, means adapted to advance a sheet to a predetermined position, a reciprocating member adapted to advance said sheet and deposit it upon a slower-moving means, which is adapted to place said sheet against stops.

3. In a sheet-feeding machine, means adapted to advance a sheet to a predetermined position, a reciprocating member adapted to advance said sheet and deposit it upon power-driven tapes, which is adapted to place said sheet against stops.

4. In a sheet-feeding machine, means to advance a sheet to a predetermined position, a reciprocating member adapted to forward said sheet and deposit it upon a carrier, which is adapted to place said sheet against stops.

5. In a sheet-feeding machine, means

- adapted to advance a sheet to a predetermined position, a front frame containing power-driven tapes, which is adapted to place a sheet against stops, a reciprocated member adapted to advance a sheet and deposit it upon said tapes.
6. In a sheet-feeding machine, means adapted to advance a sheet to a predetermined position, a frame containing power-driven tapes, adapted to place a sheet against stops, a reciprocated member adapted to engage a sheet and deposit it upon the said tapes.
7. In a sheet-feeding machine, a power-rotated tape-roll carrying tapes, a power-operated drop-roll, adapted to contact said tapes, means to place a sheet between said drop-roll and said tapes, means adapted to place a sheet against stops, a reciprocated member adapted to advance a sheet and deposit it upon the aforesaid means.
8. In a sheet-feeding machine, a power-rotated main tape-roll carrying tapes, a drop-roll, adapted to contact said tapes, means to place a sheet between said drop-roll and said tapes, a front frame containing power-driven tapes, which is adapted to place a sheet against stops, a reciprocated member adapted to advance a sheet and deposit it upon said front tapes.
9. In a sheet-feeding machine, a main power-rotated tape-roll carrying tapes, a power-operated drop-roll adapted to contact said tapes, means to place a sheet between said drop-roll and said tapes, a front frame containing power-driven tapes, adapted to place a sheet against stops, the aforesaid front-frame tapes traveling at a slower speed than the aforesaid main tape-roll tapes, means to advance a sheet from the fast-running tapes to the slow-running tapes.
10. In a sheet-feeding machine, a main power-rotated tape-roll carrying tapes, a power-operated drop-roll adapted to contact said tapes, means to place a sheet between said drop-roll and said tapes, a front frame containing power-driven tapes, adapted to place a sheet against stops, the aforesaid front-frame tapes traveling at a slower speed than the aforesaid main tape-roll tapes, a reciprocated member adapted to engage a sheet and deposit said sheet upon the front slow-running tapes.
11. In a sheet-feeding machine, a power-rotated main shaft, a rock shaft in operative connection with said main rotating shaft, a framing containing means adapted to place a sheet against stops, ways mounted in said framing, a reciprocating member mounted upon said ways having gripper mechanism adapted to take hold of a sheet and means to operate said grippers, operative connections between said rock shaft and said reciprocating member.
12. In a sheet-feeding machine, a power-rotated main shaft a rock shaft in operative connection with aforesaid rotating shaft, a framing containing power driven tapes adapted to place a sheet against stops, ways mounted in said framing, a reciprocating member mounted on said ways and adapted to engage a sheet, operative connections between said rock shaft and said reciprocating member.

JAMES G. HARDIE.
